UNITED STATES PATENT OFFICE.

GEORGE P. FISHER, OF CHICAGO, ILLINOIS.

BUTTON-LOOP FOR GARMENT-SUPPORTERS.

1,198,017.

Specification of Letters Patent. Patented Sept. 12, 1916.

Application filed April 20, 1916. Serial No. 92,345.

To all whom it may concern:

Be it known that I, GEORGE P. FISHER, a citizen of the United States, residing at Chicago, in the county of Cook and State of Illinois, have invented certain new and useful Improvements in Button-Loops for Garment-Supporters, of which I do declare the following to be a full, clear, and exact description, reference being had to the accompanying drawing, forming part of this specification.

The present invention has relation more particularly to garment supporter button loops such as are used for garters, in which the upper part of the loop has its side members sufficiently separated to admit the head of a button and part of the garment to be supported, while the lower part of the loop is of a width narrower than the head of the button and is provided at its bottom with a pad of rubber or like material. Examples of this type of garment supporter loop are shown in Patent No. 838,643, Pilkington, December 18, 1906, and Patent No. 1,049,912, Pilkington, January 7, 1913.

The invention consists in the features of novelty hereinafter described, illustrated in the accompanying drawing and particularly pointed out in the claims at the end of this specification.

Figure 1 is a view in elevation of a garment supporter loop embodying my invention. Fig. 2 is a view similar to Fig. 1, the pad at the bottom of the loop being shown in section, the upper portion of the loop being omitted. Fig. 3 is a view similar to Fig. 2 but showing a modified form of the invention. Fig. 4 is a view similar to Fig. 2 but showing a further modification of the invention. Fig. 5 is a detail perspective view of one form of rubber pad for the lower end of the loop. Fig. 6 is a detail view of a slightly modified form of pad.

The loop is preferably formed of a wire having side members *a*, the upper ends of which are bent inward and united by a metal sleeve or tube *b*. The side members of the upper portion of the loop are expanded in the usual manner to receive the head of the button and a portion of the stocking or other garment to be supported, while the lower portions of the side members are brought more closely together and are separated at a distance less than the diameter of the head

of the button, the shank of which will be received between the contracted lower portions of the side members.

At its lower end my improved garment supporter loop is provided with an upstanding pad holder *c* between the side members *a*, and slightly spaced therefrom. Preferably, the side members are bent slightly to form inward projections *d* adjacent the upper part of the pad holder *c*. Upon the pad holder *c* is mounted a pad *e* preferably of rubber. This pad *e* may be applied to the pad holder in different ways and may consist of a molded pad or of a short section of a rubber tube slipped over the pad holder after the loop has been formed. Preferably, the pad *e* consists of a short section of rubber tubing, as shown in Figs. 5 and 6, having a small bore and this section of tubing is forced down over the upstanding pad holder so as to fill the space between the side walls of the pad holder and the side members *a* of the loop. The resiliency of the material tends to securely retain the pad in position upon the pad holder and the inward projections *d* of the side members *a* also aid in preventing any accidental withdrawal of the pad from the pad holder.

In the form of the invention shown in Fig. 3 of the drawings, a somewhat different shape is given to the upstanding pad holder in order to enable it to more effectively retain the pad in position at the bottom of the loop; that is to say, the upper part of the pad holder is expanded as at *c*².

In the form of the invention shown in Fig. 4, the lower portion of the wire of which the supporter loop is formed is bent to form an upstanding pad holder *c*' somewhat circular in shape, the members *a* of the wire crossing each other as at *a*' at the bottom of the loop and, if desired, slightly flattened at their point of intersection. After the loop has thus been formed, the pad *e* may be applied thereto either as a molded piece of rubber or as a section of a tube.

If desired, the tubing from which the pads *e* are cut may be formed with grooves *e*² at opposite sides to receive the side members *a* of the loop, although even in the absence of such grooves, the resiliency of the material of the pad will cause it to slightly overlap the side members *a* of the loop. So, also, if desired, after the pad has been placed

upon the pad holder, the slight opening in the pad may be closed by rubber cement or the like, although this is not essential.

Having thus described my invention, what I claim as new and desire to secure by Letters Patent is—

1. A button loop for garment supporters having the lower ends of its side members upturned to form a pad holder arranged between and spaced from said side members, and a pad having a vertically disposed opening to receive said pad holder and arranged between the same and the lower ends of said side members and projecting above said pad holder.

2. A button loop for garment supporters having a contracted lower portion and an arch extending upwardly from and connecting the lower ends of the side members 20 of the loop, and a pad fitting over said arch and projecting above the same.

3. A one-piece button loop for garment supporters having a contracted lower portion provided at its end with an upstanding 25 pad holder extending between and spaced from said side members, and a pad of elastic material stretched horizontally over said pad holder and projecting above the same.

4. A button loop for garment supporters 20 formed of an integral piece of metal having side members and a contracted lower por-

tion, and an upstanding arch having an expanded upper part between the side members of said lower portion, and a pad mounted upon said arch.

35

5. A one-piece button loop for garment supporters having a contracted lower portion provided at its ends with an upstanding pad holder extending between and spaced from said side members, and a pad 40 fitting over said holder and gripped between the same and the lower ends of the side members.

6. A button loop for garment supporters having a contracted lower portion and a pad 45 holder extending upwardly from the bottom of the side members of said button loop and narrower than the space between them, and a vertically disposed pad formed of open-ended rubber tubing stretched over said 50 pad holder and projecting above the same.

7. A button loop for garment supporters having side members and a contracted lower portion formed of a single piece of bent wire, said contracted portion being provided 55 at its bottom with an upstanding pad holder integral with and lying between said side members, and a pad fitting over said pad holder and extending between it and the lower end of said side members.

GEORGE P. FISHER.
